COMBINED WALL SWITCH PLATE AND PUSH-BUTTON ASSEMBLY

Samuel J. Koch, Great Neck, N. Y.

Application October 8, 1957, Serial No. 48,005

Term of patent 14 years

(Cl. D26—13)

Fig. 1 is a front elevational view of a combined wall switch plate and pushbutton assembly, showing my new design;

Fig. 2 is a side elevational view, the opposite side being substantially a mirror image thereof;

Fig. 3 is a top plan view; and

Fig. 4 is a cross-sectional view thereof taken along line 4-4 in Fig. 1.

The dominant features of my new design are shown in solid lines in the drawing.

I claim:

The ornamental design for a combined wall switch plate and pushbutton assembly, substantially as shown and described.
